UNITED STATES PATENT OFFICE.

FRED J. HOYT, OF CHICAGO, ILLINOIS.

ORE SEPARATOR AND AMALGAMATOR.

SPECIFICATION forming part of Letters Patent No. 484,933, dated October 25, 1892.
Application filed December 15, 1891. Serial No. 415,144. (No model.)

To all whom it may concern:

Be it known that I, FRED J. HOYT, a citizen of the United States, residing at Chicago, in the county of Cook and State of Illinois, have 5 invented certain new and useful Improvements in Ore Separators and Amalgamators; and I do hereby declare the following to be a full, clear, and exact description of the invention, such as will enable others skilled in the 10 art to which it appertains to make and use the same.

My invention relates to ore separators and amalgamators for the treatment of tailings and free milling-ore; and it consists of the apparatus as hereinafter described and particularly claimed.

My invention is illustrated in the accompanying drawings, in which—

Figure 1 is a view in elevation, partly in 20 section, and Fig. 2 a plan, of the amalgamating-pan.

Referring to the drawings, A is a central rotating shaft having bearings in a suitable frame B and driven in the usual way by any 25 desired power.

E is a circular pan attached to the shaft A. It is divided into sections C by walls C', which have a rounded top, and its outside peripheral wall is provided with a flat smooth 30 outwardly-projecting ring-plate a. The upper surface of this plate is on a level with the tops of the section-walls C'.

The section nearest the plate a, and which is designated as b, is made narrower than the 35 sections c, for the purpose hereinafter described. The plate a may be, say, five or six inches wide, the section b two inches wide, and the sections c four to five inches wide.

D is a fine perforated screen secured to 40 shaft A and set at an incline therefrom. Both the pan E and the screen D at their outer peripheries terminate short of the side frame B', so that material thrown off therefrom by the centrifugal force given by the rotation of the 45 shaft may fall on an inclined trough F, extending around the apparatus and which is provided with a discharge-spout K.

G is a stationary water-distributer above 50 the screen D and provided with openings f.f.

H is a hopper or chute for conducting the mingled powdered ore and sand and dirt onto 55 the screen D and to a point on the screen adjacent to the central shaft.

The operation of the apparatus as thus far described is as follows: Quicksilver to a small amount or to an extent which practice may determine as desirable, but preferably nearly the height of the walls C', or to a point where the top of the walls begin to curve, is distributed in the sections C, but not in the outer 60 section b. The mixed powdered ore, sand, and other material are carried through the chute H onto the screen D. The central shaft A having been started gives to screen D and pan E a quick rotary motion. The coarser waste 65 material is carried off the screen D by centrifugal force into the trough F. At the same time and by the same force the powdered sand and ore are spread over the screen D and fall through that screen onto the pan E and are 70 distributed in the sections c. The powdered ore is caught and retained by the quicksilver in the sections C, while the sand is forced by centrifugal action to the periphery of the pan E onto the ring-plate a and falls into the 75 trough F. The object of the dividing sections is to permit the apparatus to be run at great speed by confining and holding the quicksilver, and thereby preventing the same being thrown by the centrifugal action off the 80 pan and into the surrounding trough. The outer section b is not provided with quicksilver and naturally would soon fill up with sand; but should any of the quicksilver in sections 85 C be disturbed and carried out therefrom by the centrifugal force it would in reaching section b, by its weight displace the sand and be retained in that section instead of passing on and off the plate a with the sand, and thus be lost. The section b is made narrower than 90 the other sections for the purpose of not retarding more than is necessary the outward flow of the sand by centrifugal action, the only object of such section being to catch any quicksilver that may be displaced from the 95 other sections. As the material is fed onto the screen D it may be subjected to a bath and thoroughly washed by water forced through spout I onto distributer G and through openings f.f. When the ore is in a very finely- 100 powdered condition, the apparatus may be used without rotating the pan and the screen

D, and in such case the sand and powdered ore may be forced through the screen D by the action of the water from above and the sand and other foreign material forced out of the pan E by the same means. The pan E may also in certain cases be used without the sections c, in which case the quicksilver would be evenly distributed over the entire bottom of the pan. At the close of a run the ore and quicksilver may be removed from the pan by any suitable means.

By my invention the pulp may be fed in a continuous stream through the mill and spread over a large body of quicksilver, thus enabling large quantities of material to be treated in a very short time.

In certain cases where the pulp is all in powdered form of a specific size it might not be necessary to use the screen alone and the ore could be fed directly on the pan from the chute.

Having thus described my invention, what I claim is—

1. In an ore separator and amalgamator for treating powdered ore, the combination, with a central rotary vertical shaft, of an amalgamating-pan secured to said shaft, and provided with annular walls c, having rounded tops and dividing the pan into annular sections c for containing the amalgam, an outer narrower annular section b, and a peripheral rim a, whereby when powdered ore is fed to

said pan and motion is given to said shaft the sand and other light refuse are thrown over the rim by centrifugal action and the amalgam displaced by said action from sections c is caught in section b, substantially as described.

2. In an ore separator and amalgamator for treating powdered ore, the combination, with a central vertical shaft, of an amalgamating-pan secured to said shaft and on which the quicksilver is distributed, an ore-screen above said pan and also secured to said shaft, inclining upwardly from the shaft, and extending outwardly above the periphery of the pan, an inclined trough extending around the apparatus and around and below the peripheries of said pan and screen, a stationary water-distributer provided with openings located above said screen and adapted to distribute the water over its surface, a water-spout to conduct water to the said water-distributer, said trough provided with a discharge-spout, and the apparatus also provided with a hopper or chute to conduct the powdered ore onto the ore-screen, substantially as described.

In testimony whereof I affix my signature in presence of two witnesses.

FRED J. HOYT.
